NEEDLE FOR KNITTING-MACHINES.

1,035,752.

Specification of Letters Patent. Patented Aug. 13, 1912.

Application filed June 1, 1908. Serial No. 436,040.

To all whom it may concern:

Be it known that I, ROBERT W. SCOTT, a citizen of the United States, residing in Leeds Point, Atlantic county, New Jersey, 5 have invented certain Improvements in Needles for Knitting-Machines, of which the following is a specification.

My invention relates to that class of knitting machine needles which employ a sliding member in place of the usual pivoted and swinging latch for the purpose of closing the hook of the needle and casting off the old stitch when the new loop is being drawn through the latter, the object of my 10 invention being to provide a simple, cheap and effective needle of this class intended especially for use in machines of fine gage. This object I attain in the manner herein-after set forth, reference being had to the 15 accompanying drawing, in which—

Figure 1 is a vertical sectional view of sufficient of a knitting machine to illustrate my present invention, the needle being shown in the elevated position where its 20 hook engages the knitting yarn; Fig. 2 is a similar view showing the parts in the positions assumed by them when the needle has been partially retracted and is about to draw the new loop through the preceding stitch; Fig. 3 is a view, showing the relation of the 25 parts when the new loop has been drawn; Fig. 4 is a view, showing the relation of the parts, preparatory to the rise of the hooked member of the needle to again receive the knitting yarn; Fig. 5 is a similar view, 30 showing a different operation which may sometimes be resorted to; Figs. 6 and 7 are enlarged views of part of the needle showing the sliding member at the opposite extremes of its movement in respect to the 35 hooked member; Fig. 8 is a section on the line $a-a$, Fig. 6, and Figs. 9, 10 and 11 are views illustrating modified forms of the 40 needle.

An ordinary knitting machine latch needle 45 is objectionable for many reasons, among which may be mentioned the length of travel of the needle; the weakening of the same by the latch-receiving slot and the 50 transverse pivot-pin openings; the delicacy

of the latch and its pivot pin; the wear upon the latter; the liability of the latch to become broken or bent, thus rendering the needle inoperative; the necessity for the use, in connection with the latch, of an opener 55 therefor, in order to insure the clearing of the hook of the needle for the reception of the fresh yarn; the number of operations necessary to produce the needle, and the consequent cost of the same. 60

An ordinary latch needle must have a reciprocating movement exceeding twice the length of its latch, and, as the effective working angle of a needle-actuating cam cannot be greater than 45° , such cams occupy 65 so much space in the cam cylinder, that, in machines of small diameter the use of more than one yarn feed is generally impracticable.

The substitution of a sliding hook-closing 70 member for the swinging latch obviates the objections above noted, but, while needles having such sliding members have heretofore been proposed, they have not supplanted the latch needle because they have 75 not been adapted for use in the fine gage machines now employed for knitting hosiery and underwear. My invention has, therefore, been designed with the view of providing a needle of this type which is capable 80 of use in machines having a gage as fine as, or finer than, those now employed.

In the drawing, 1 represents part of a cylinder, straight-bed, dial, or other needle-carrying member of a knitting machine 85 (hereinafter, for convenience, termed a "cylinder") and 2 represents part of a cam ring, cam-carrying plate, or other cam member of the machine (hereinafter, for convenience, termed a "cam ring.") The cylinder has needle grooves 3, and each needle 90 comprises a hooked member 4 and a jack 5, the hooked member having the hook 6 at its outer end, a face groove 7 with cam formation 9 at its outer end and a butt 10 to be 95 acted upon by a projecting cam 11 and a retracting cam 12 on the cam ring 2, whereby the longitudinal reciprocation of the hooked member of the needle in its respective groove of the needle cylinder is effected, 100

these cams being smaller than the usual cams, however, because of the lesser movement of the needle required as compared with that of a needle having a swinging latch. The groove 7 receives a spring tongue 13, which is secured to or forms part of the jack 5, and the latter bears against the face of the member 4, is guided with the latter in the groove 3 of the cylinder and has a butt 14 to be acted upon by a projecting cam 15 and a retracting cam 16 carried by the cam ring 2, as shown in Figs. 1 and 2.

As shown in Fig. 1, the hooked member of the needle has been projected so that its hook engages the knitting yarn x , the preceding stitch y lying on top of the needle cylinder and the spring tongue 13 being contained within the groove 7. As the hooked member of the needle is retracted by means of the cam 12, the jack 5 may either remain stationary or may be projected by the cam 15. In either case, the cam formation 9 will engage the upper end of the tongue 13 and throw the same outwardly, and by the time the hook 6 reaches the upper end of the tongue, the latter will be in position to overlap and close said hook, as shown in Fig. 7. Both the hooked member and the jack are now retracted together, and the spring tongue 13 continues to perform its function of closing the hook until the latter has been drawn down through the previous stitch y , the latter has been cast over the hook and the new stitch has been drawn, as shown in Fig. 3. The retraction of the spring tongue 13 may continue until the upper end of said tongue has been withdrawn into the groove 7, as shown in Fig. 4, whereupon both the hooked member and the jack 5 may be projected together until the stitch has been slipped back of the upper end of the groove 7, as shown in Fig. 1, and the knitting yarn is again engaged by the hook 6 preparatory to a repetition of the operations above described. As an alternative to this method of operation, the hooked member of the needle may, after the parts reach the retracted position shown in Fig. 3, be projected alone, as shown in Fig. 5, the tongue 13 springing back into the groove 7, as the cam formation is withdrawn from behind it, and being then projected with the hooked member 4 so as to pass through the stitch, and into position for being again projected by the cam formation 9 when the hooked member is retracted.

While, I prefer, in all cases, to groove the face of the hooked member of the needle for the reception of the spring tongue 13, my invention also contemplates the use of a spring tongue lying against the inner face of said hooked member, as shown, for instance, at 4^b in Fig. 9. I also prefer to operate the jack 5 by means of cams in the cam ring, but the movements of said jack in

respect to the hooked member of the needle may be due to the movements of the latter if desired, instances of such construction of the needle being represented in Figs. 10 and 11. Each of the needles shown in these figures has a jack 5^a provided with an elastic finger 17 for bearing against the walls of the needle groove and causing such frictional retardation of the jack that it can only be moved by positive pressure exerted through the medium of the hooked member 4^a of the needle. This pressure may be exerted by means of properly placed lugs or bits 19 upon the hooked member as shown in Fig. 10, these lugs contacting alternately with the top and bottom of the jack, to move the same at the proper times, or the hook 6 may contact with the upper end of the spring tongue 13^a, as shown in Fig. 11, to effect the downward movement of said tongue with the hooked member of the needle after it has been sprung outwardly by the cam member 9 of the same, the upward movement of the jack and its tongue being effected by contact of a lug or bit 20 with the bottom of the jack.

Even when the face of the needle is grooved, said needle is simpler, cheaper and stronger than the usual needle, slotted and drilled for the reception of a latch and its pivot pin, and, as the jack, with its spring tongue, can be as thin as desired, the needle can be made for use in machines of the finest gage, being free from the determining factors which serve to limit the size of an ordinary latch needle.

As the necessary reciprocating movement of a needle made in accordance with my invention, is less than that of a latch needle, the space occupied by the needle-actuating cams can be correspondingly reduced, and a machine of small diameter can be equipped with two or more yarn feeds, where only one such feed is now practicable.

I claim:

1. A knitting machine needle having a shank with forwardly projecting hook and a cam formation below the same, with a jack movable longitudinally in respect to the shank of the needle and normally lying close to said shank, the forward end of the jack, however, being elastic whereby when the jack is projected its forward end will be acted upon by the cam formation of the needle shank and will thereby be caused to follow an inclined path so that when fully projected it will overlap and contact with the point of the projecting needle.

2. A knitting machine needle having a shank with forwardly projecting hook, a groove in the front face of the shank, and a cam formation at that end of the groove which is adjacent to the hook, in combination with a spring jack movable longitudinally in respect to the shank of the needle

and normally lying snugly against the base of the groove but when projected being acted upon by the cam formation at the end of said groove and being thereby moved out-
wardly and caused to follow an inclined course so that when fully projected it will overlap the point of the hook.

In testimony whereof, I have signed my name to this specification, in the presence of two subscribing witnesses.

ROBERT W. SCOTT.
